F. B. BECKWITH,
GARMENT STRETCHER,
APPLICATION FILED FEB. 5, 1915.

1,146,991.

Patented July 20, 1915.

Fig. 1.

UNITED STATES PATENT OFFICE.

FRANKLIN B. BECKWITH, OF OCONEE, NEBRASKA.

GARMENT-STRETCHER.

1,146,991.

Specification of Letters Patent. Patented July 20, 1915.

Application filed February 5, 1915. Serial No. 6,207.

To all whom it may concern:

Be it known that I, FRANKLIN B. BECKWITH, a citizen of the United States, residing at Oconee, in Platte county, in the State of Nebraska, have invented certain new and useful Improvements in Garment-Stretchers, and have described the same in the following specification, illustrated by the accompanying drawings.

10 My invention relates to that class of stretchers which are used for shaping and creasing trousers, and which individually comprise a deformable flat frame for insertion in a leg of the garment.

15 It is the object of the invention to render apparatus of this kind simple in construction, easy to be assembled for use, noncollapsible when so assembled, and capable of being symmetrically disassembled and readily folded into small space and convenient shape for packing and transportation; and in general to produce a superior utensil of the specified class. To accomplish this object I incorporate in my improved pants 20 creaser, as parts thereof, a pair of longitudinally disposed side bars which are detachably fastened together by turnbuckle links, and are severally provided with a hinge joint and a latch and are sharpened along 25 the outer edge of each bar.

In said drawings, illustrating the best manner in which I have contemplated applying the principles of the invention, Figure 1 is a side elevation of a garment 30 stretcher which is constructed in accordance with these principles, and is assembled and distended as in actual use. Fig. 2 is an opposite side elevation of one of the side bars of the same apparatus, including the permanent attachments of that bar, those attachments being turned pivotally into parallelism with the longitudinal axis of the bar in preparation for folding the hinged portions of the bar together. Fig. 3 is an 40 edge elevation of the same side bar and attachments in the same position. Fig. 4 is a side elevation of the same side bar and attachments, collapsibly folded together. Fig. 5 is a transverse section on the broken line 45 A—A in Fig. 1. Fig. 6 is a side elevation of one of the turnbuckle links, including its terminal clasps for engaging the side bars. Fig. 7 is an edge elevation of the same. Fig. 8 is a side elevation of one of the two latches 50 bars which are respectively pivoted to the

side bars. Fig. 9 is an edge elevation of the same.

In the illustrated specimen of my invention, each of the side bars 1 and 2, being of metal, preferably aluminum, consists of two 50 terminally abutting and slightly tapering half bars denoted by the same numerals and united at the middle and widest part of the bar by the hinge 3. Along its entire length each bar is beveled to a thin outer edge 4, 55 as instanced in Fig. 5. This edge, extending beyond the projecting parts of the hinge 3, is unobstructedly smooth, sharp and straight, when the bar is extended by unfolding. Each of the side bars is provided 60 with a latch comprising the latch bar 5, which is pivoted to one of the half bars by the pin 6, and is adapted to span the hinge joint, as well as to engage by its slot 7 the catch pin 8 projecting from the other half 65 bar. Operatively the side bars are adjustably spaced apart in approximately parallel positions by the connecting turnbuckle links 9, one of which is shown separately in Figs. 6 and 7. Each link comprises two alining screw rods 10 and 11, a turnbuckle 12, working thereon to lengthen and shorten the link as may be desired, and two terminal shoes, or clasps 13 and 14, for connecting these rods to the side bars. Each 70 of these clasps, being formed of a folded plate of steel or other similarly elastic material, has two parallel cheeks, or leaves, 15, spaced apart but united along the back edge 16, and is firmly attached to the outer 75 end of one of the screw rods, in alinement therewith. The clasp 13, with its leaves 15 in contact with the opposite sides of one of the side bars, is permanently attached thereto by the pivot pin 17; while the clasp 14, 80 with its leaves similarly gripping the other side bar, is secured thereto detachably by means of the slots or holes 18 and 19 in those leaves and the pins or lugs 20 and 21 85 projecting laterally from that bar on both sides, these pins and holes being positioned so as to register with each other respectively when the mechanism is assembled for use, and being adapted to prevent the last-mentioned clasp from turning rotatively upon 90 either of these pins. Accordingly the entire apparatus, when assembled for use, is prevented from collapsing by these detachable clasps, sprung into position upon the pins 20 and 21, and by the latches 7, 8. To 95

facilitate assembling, pin 21 is made of such size or shape that it cannot catch in the slot 19 passing over it.

When the apparatus is assembled as in Fig. 1, the side bars are adjusted to the work at a greater or less distance apart by manipulation of the turnbuckles in an obvious and usual manner. When not in use, the utensil may be disassembled by forcibly springing the clasps 14 from the side bars respectively, and by then turning the links pivotally on the pins 17 into positions along and against the side bars to which they are respectively pivoted. The spring clasps 14 then severally engage those bars between the clasp leaves 15, while the links in their entirety are held thereby compactly in the positions just described. The latch bars 5 being swung pivotally to the position shown in Fig. 2, the entire structure can then be folded together as in Fig. 4 for convenience in packing and transporting the same.

I claim as my invention—

1. A garment stretcher of the specified class, comprising a pair of side bars, a pair of turnbuckle links between them, a pivoted clasp connecting each link with one of the bars, and a spring clasp detachably connecting the same link with the other bar.

2. A garment stretcher of the specified

class, comprising a pair of side bars, a pair of turnbuckle links between them, and a pair of aligning connections carried by each link and fitted to clasp either both or one only of the bars as may be desired.

3. A garment stretcher of the specified class, comprising a pair of side bars adjustable toward and from each other, a pair of turnbuckle links between them, a pivotal connection between each link and one of the side bars, and a spring clasp carried by the link and adapted to engage the side bars respectively.

4. A garment stretcher of the specified class, comprising a pair of side bars adjustable toward and from each other, a pair of transverse links of adjustable length between them, a pivotal connection between each link and one of the side bars, and a two-leaved spring clasp carried by each link and adapted to hold the other side bar in a fixed position relatively to the clasp-carrying link.

In testimony whereof I subscribe this specification in the presence of two witnesses.

FRANKLIN B. BLACKWELL.
